(57) **CLAIM**

The ornamental design for a varying elliptical reflector, as shown and described.

DESCRIPTION

FIG. 1 is an isometric view, from the front and above, of a varying elliptical reflector in accordance with the present invention.

FIG. 2 is a right side elevational view of the varying elliptical reflector of FIG. 1, the left side elevational view being a mirror image thereof.

FIG. 3 is a top plan view of the varying elliptical reflector of FIG. 1.

FIG. 4 is a front elevational view of the varying elliptical reflector of FIG. 1.

FIG. 5 is a bottom plan view of the varying elliptical reflector of FIG. 1.

FIG. 6 is a rear elevational view of the varying elliptical reflector of FIG. 1.

FIG. 7 is an isometric view, from the back and above, of the varying elliptical reflector of FIG. 1.

FIG. 8 is an isometric view, from the front and above, of an alternative embodiment of the varying elliptical reflector in accordance with the present invention.

FIG. 9 is a right side elevational view of the varying elliptical reflector of FIG. 8, the left side elevational view being a mirror image thereof.

FIG. 10 is a top plan view of the varying elliptical reflector of FIG. 8.

FIG. 11 is a front elevational view of the varying elliptical reflector of FIG. 8.

FIG. 12 is a bottom plan view of the varying elliptical reflector of FIG. 8.

FIG. 13 is a rear elevational view of the varying elliptical reflector of FIG. 8; and,

FIG. 14 is an isometric view, from the back and above, of the varying elliptical reflector of FIG. 8.
